FIG. 4.

INVENTOR

George Lotysiewicz,
BY Oscar Geier

ATTORNEY

UNITED STATES PATENT OFFICE.

GEORGE LOTYSIEWICZ, OF BROOKING, SASKATCHEWAN, CANADA.

BOMB-DROPPER.

1,278,955.

Specification of Letters Patent. Patented Sept. 17, 1918.

Application filed March 30, 1918. Serial No. 225,643.

To all whom it may concern:

Be it known that I, GEORGE LOTYSIEWICZ, a citizen of Poland, and a resident of Brook-
ing, in the Province of Saskatchewan, Do-
minion of Canada, have invented certain new
and useful Improvements in Bomb-Drop-
pers, of which the following is a specifica-
tion.

This invention relates to improvements in
10 apparatus for dropping bombs or other like
explosives, and has as its special object the
provision of means, engageable with a bal-
loon or airship of any kind whatever, where-
by one or more bombs may be freed from
15 their carrier and allowed to drop by gravity
upon the ground below.

A further object is to provide a discharg-
ing or disengaging means in such manner
20 as to be convenient of access to the operator
within the car attached to the air craft which
may be employed.

These and other like objects are attained
by the novel construction and combination of
25 parts hereinafter described and shown in
the accompanying drawing, forming a ma-
terial part of this disclosure, and in which:—

Figure 1 is a side elevational view, par-
tially in section showing an apparatus made
in accordance with the invention.

30 Fig. 2 is an enlarged horizontal sectional
view, taken on line 2—2 of Fig. 1,

Fig. 3 is a further enlarged transverse sec-
tional view taken on line 3—3 of Fig. 2, and

35 Fig. 4 is a fragmentary horizontal sec-
tional view, taken on line 4—4 of Fig. 3.

In the drawings, the numeral 10, design-
ates the balloon, or air craft, here shown to
be of conventional type, from which is sus-
pended, the car 11, by means of supports or
40 guy rods 12, as is usual. Attached at the
center below the car by means of a bar 14, is
a rigid circular plate 15, containing a plu-
rality of openings 16, formed in a row con-
centric with the plate or disk 15, the same
45 being recessed as at 17 in its lower side, the
openings 16 being adapted to receive the
conical bodies of the bombs 20, which are
provided with time fuses 21, or like devices
upon their upper ends, while the lower ends

22 contain a high explosive adapted to be 50
detonated by concussion with the surface
upon which the bomb alights.

Formed radially in the plate, 15, adjacent
to the openings 16 are other openings 24,
having downwardly extending recesses 25, 55
and into which are rotatably mounted cams
28, the same being secured to stems 29, by
pins 30, the lower ends of the stems 31 being
reduced in diameter and extended through
the bottom of the plate 15.

60 Fixed upon the stem 31 are rectangular
blocks 32, normally resting in appropriately
formed openings at the bottom of the re-
cesses 25 and coiled about the lower ends of
the stems 29, are springs 33, one end of which
65 is engaged in the bottoms of the recesses 25,
the other end being secured to the lower por-
tion of the cams 28, so as to cause a rotary
movement of the stems when the blocks are
70 raised which causes the cams to engage with
the periphery of the bombs 20, thereby hold-
ing them in suspension under normal cir-
cumstances.

Arranged at the tops of the stems 29, are
75 handles 35, by means of which the stem may
be partially rotated, overcoming the tor-
sional effect of the springs when it is desired
to liberate the bomb.

In operation, the bombs having been as-
sembled in the disk or plate 15, which is at-
tached by the rod or bar 14 to the car so
that handles 35 project upward to be con-
veniently operated by a person in the car, the
device is in condition to ascend and travel
over the territory where it is desired to drop
the bomb, which obviously is accomplished
80 by operating the handle 35, thereby liberat-
ing the bomb, the fuses 21 having been set at
the proper time interval, or reliance may be
placed upon the detonating elements 22 at 85
90 their ends.

Having thus described my invention what
I claim as new and desire to secure by Let-
ters Patent, is.

In a bomb carrier, the combination with 95
an aerial apparatus, and a car suspended
therefrom, of a circular plate suspended
from said car, said plate having a plural-

ity of recessed openings, bombs engageable within said openings, said bombs being adapted to pass therethrough, cams mounted contiguous to said openings, the face of said 5 cams being contactable with the periphery of said bombs, means for normally causing contact therebetween, stems engaged with

said cams extending upward into said car, and means for rotating said stems whereby said bombs may be released.

In testimony whereof, I have affixed my signature.

GEORGE LOTYSIEWICZ.
